UNITED STATES PATENT OFFICE

143,847

DESIGN FOR AN AIRPLANE

John K. Northrop, Los Angeles, Calif., assignor to
Northrop Aircraft, Inc., Hawthorne, Calif., a
corporation of California

Application May 10, 1940, Serial No. 92,284

Term of patent 14 years

(Cl. D71—1)

To all whom it may concern:

Be it known that I, John K. Northrop, a citizen of the United States of America and resident of Los Angeles, county of Los Angeles, State of California, have invented a new, original, and ornamental Design for an Airplane, of which the following is a specification, reference being had to the accompanying drawing, forming part thereof.

Fig. 1 is a front elevational view of the airplane in flight posture, showing my new design.

Fig. 2 is a top plan view of the airplane.
Fig. 3 is a side elevational view of the airplane.
Fig. 4 is a perspective view of the airplane in accordance with this design, the angle of view being taken from above and slightly forward of the plane in flight.

I claim:
The ornamental design for an airplane, as shown.

JOHN K. NORTHROP.
